(57) **CLAIM**

The ornamental design for a light, substantially as shown and described.

DESCRIPTION

FIG. 1 is a first side view of a first embodiment of a light showing my ornamental design with an adjustable head shown in an extended position;

FIG. 2 is a second side view thereof;

FIG. 3 is a third side view thereof;

FIG. 4 is a fourth side view thereof;

FIG. 5 is a rear end view thereof;

FIG. 6 is a front end view thereof;

FIG. 7 is a first side view of a second example embodiment of a light showing my ornamental design with the adjustable head shown in an extended position;

FIG. 8 is a second side view thereof, of which a third side view is the same as shown in FIG. 3;

FIG. 9 is a fourth side view thereof;

FIG. 10 is rear end view thereof;

FIG. 11 is a front end view thereof;

FIG. 12 is the first side view thereof with the adjustable head shown in a closed position;

FIG. 13 is the second side view thereof with the adjustable head shown in a closed position;

FIG. 14 is the fourth side view thereof with the adjustable head shown in a closed position;

FIG. 15 is the first side view thereof with the movable ring shown in a different position;

FIG. 16 is a second side view thereof with the movable ring shown in a different position;

FIG. 17 is a first side view thereof with the movable ring shown in a different position and the adjustable head shown in an extended position;

FIG. 18 is a second side view thereof with the movable ring shown in a different position and the adjustable head shown in an extended position;

FIG. 19 is a first side view of the first embodiment with the movable ring shown in a different position; and,

FIG. 20 is a second side view thereof with the movable ring shown in a different position.

Broken lines in the illustrations of the FIGURES of the drawing indicate parts of the article that are not part of the design illustrated therein.
